UNITED STATES PATENT OFFICE.

CLEMENT B. TOWER, JR., OF HYDE PARK, MASSACHUSETTS.

AMUSEMENT DEVICE.

Specification of Letters Patent.

Patented May 23, 1911.

993,282.

Application filed July 8, 1907. Serial No. 382,592.

To all whom it may concern:

Be it known that I, CLEMENT B. TOWER, Jr., a citizen of the United States, residing at Hyde Park, in the county of Norfolk, 5 State of Massachusetts, have invented an Improvement in Amusement Devices, of which the following description, in connection with the accompanying drawings, is a specification, like letters on the drawings representing like parts.

This invention relates to an amusement device which may be best understood by reference to the accompanying drawings, which show a preferred illustrative embodiment.

In the drawings: Figure 1 is a front elevation of the illustrative embodiment referred to; Fig. 2, a perspective showing the device with its front removed; and Fig. 3, a 15 perspective of a part hereinafter described. Fig. 4 is a central longitudinal section of the device showing the body and face members and a containing member, all assembled.

The specific device shown in the drawings 20 comprises a hollow body portion A, having its rear preferably permanently closed and its front closed by some amusing representation such, for example, as that of a human face B. In the front closure—i. e., in the 25 face—is an aperture C, shown as the mouth of the face. In the interior of the device are one or more tongues D—D, preferably having displayed upon each of them some inscription such as "Yes," "No," etc. The 30 floor of the body portion A preferably slopes downward, supplying a slideway E which, at its lowermost edge, preferably registers with the lower extremity of the aperture C.

The tongues D—D are preferred to be 35 loose in the interior of the amusement device and said tongues may be formed integrally or otherwise fastened together, or they may be separate. As illustrated in Fig. 3, there are four tongues extending radially 40 from a common center and forming in effect a species of star wheel, the star wheel being loosely contained within the device.

The specific tongues D—D shown in Fig. 3 are preferably bent slightly inward toward 45 their common center, so that each will co-

operate with the slideway E as presently described. The depth of the body portion A, from front to rear, is preferably such that the specific tongues shown are prevented from turning within the device on a vertical 55 axis and are thereby maintained with their curved surfaces in proper relation to the slideway E.

In operating the preferred form shown in the drawings the device may be shaken until 60 one tongue, extending downwardly, strikes the slideway E and protrudes through the aperture C, the curvature of the tongue facilitating this movement.

The interior of the device is preferably 65 entirely inclosed, to render it impossible to ascertain which of the tongues is next to be displayed. This permits the device to be used as the agency of a guessing contest or the like.

The principle of this invention may be 70 utilized in various different ways, as will be apparent to those familiar with the art pertaining to amusement devices.

I claim as my invention:

1. An amusement device comprising, in combination, a hollow body having a front member formed in representation of a face and provided with a mouth aperture; and a plurality of connected tongues different in 80 appearance from one another and loosely contained in said body, said tongues being free to alternatively project through said aperture by chance when the device is shaken.

2. An amusement device comprising, in combination, a hollow body having a front member formed in representation of a face and provided with a mouth aperture; a slideway leading to said aperture; and a free tongue member loosely received in said body 85 and having a portion adapted to glide along said slide-way through said mouth aperture and project through the latter when the device is shaken, said member having provision for limiting its projection through 90 said aperture.

3. An amusement device comprising, in combination, a hollow body having a front member formed in representation of a face and provided with a mouth aperture; and 100

tongues differing in appearance from one another and adapted alternatively to project by chance through said aperture when the device is shaken, said tongues being 5 loosely received in said body and having provision for limiting their projection through said aperture.

In testimony whereof, I have signed my name to this specification, in the presence of two subscribing witnesses.

CLEMENT B. TOWER, JR.
